Primary Examiner — Jennifer A Rivard*Assistant Examiner* — Catherine Suzanne Posthauer(74) *Attorney, Agent, or Firm* — Caesar Rivise, PC(57) **CLAIM**

The ornamental design for a cone handrail support, substantially as shown and described.

DESCRIPTION

FIG. 1 is a top isometric view of a cone handrail support, showing my new design, in a position of use with an exemplary adapter plate.

FIG. 2 is a bottom isometric view thereof.

FIG. 3 is a front elevational view thereof.

FIG. 4 is a back elevational view thereof.

FIG. 5 is a left elevational view thereof.

FIG. 6 is a right elevational view thereof.

FIG. 7 is a top plan view thereof.

FIG. 8 is a bottom plan view thereof; and,

FIG. 9 is a top isometric view thereof, shown in an alternate

position of use with another exemplary adapter plate. The broken lines are shown for the purpose of illustrating environmental subject matter of adapter plates, and parts of the article, none of which form part of the claim.

1 Claim, 3 Drawing Sheets(56)
